UNITED STATES PATENT OFFICE.

PATRICK L. HUSSEY, OF CLEVELAND, OHIO.

STEERING-WHEEL.

SPECIFICATION forming part of Letters Patent No. 785,073, dated March 14, 1905.

Application filed June 4, 1903. Serial No. 159,983.

To all whom it may concern:

Be it known that I, PATRICK L. HUSSEY, a citizen of the United States of America, residing at Cleveland, in the county of Cuyahoga and State of Ohio, have invented certain new and useful Improvements in Steering-Wheels, of which the following is a specification, reference being had therein to the accompanying drawings.

This invention relates to improvements in hand-wheels and the like, and especially to steering-wheels for motor-vehicles and similar purposes; and its object is to provide means for so attaching the wheel to the upper end of the steering-shaft that it may be adjusted toward or from the operator for the purpose of giving free ingress to and egress from the vehicle and for convenience and ease of manipulation by different operators; and also for so attaching the wheel to the steering-shaft that when in operative position it will be as rigidly secured thereto as though it were integral therewith, a further object of the invention being to provide certain other new and useful features, all as hereinafter more fully described, reference being had to the accompanying drawings, in which—

Figure 1 is a transverse vertical section of a device embodying the invention; Fig. 2, a perspective view of the wheel, showing the under side of the same; Fig. 3, a perspective view of the upper end of the steering-shaft and head, partly in section; Fig. 4, a detail illustrating a modification having means for operating both latches at once; Fig. 5, a further modification illustrating a construction in which but one latch is used and in which the wheel has several adjustments. Fig. 6 is a perspective view of a modified form of steering-shaft and head.

As shown in the drawings, A is the vertically-extending steering-shaft, which is connected at its lower end by any suitable means (not shown) to the forward or steering-vehicle wheels to transmit motion from the hand-wheel B to turn said wheels. Keyed to the upper end of said shaft is a forging forming a supporting-head C, to which the wheel B is adjustably secured by providing said head with an undercut channel or groove

C' in the upper face of the head and forming the spider B' of the wheel with a tongue or rib B' on the under side to engage said groove. The head is provided with a forwardly-extended portion C' to give a longer groove, 55 thus allowing a greater movement of the rib B' therein, and said rib is also extended for the same purpose, being formed integral with two of the arms of the wheel-spider B' and extended across the axis of the wheel. The head is also provided with laterally-extending portions C', each formed with an opening to receive a latch D, provided with a guide-stem, upon which a coiled spring D' is sleeved to normally hold the latch projected, and 60 with a pin D'', extending through a slot in the forging and provided with a knob at its outer end by means of which the latch is operated. The two arms of the spider B' which extend oppositely to those formed with the rib are 65 each formed with a lug B'', having a notch in its side for the engagement of the latches, so that when the axis of the wheel is in line with the axis of the shaft the latches will engage these notches and hold the wheel from sliding on the head. When the latches are thus engaged, the wheel is held as rigidly in position on the shaft as though it were immovably secured thereto, because of the form of the connection or rib and groove and the 70 length of bearing which the rib has in the groove, and the operator may very readily move the wheel out of the way in getting in or out of the vehicle by pressing the latches toward each other and sliding the wheel forward, the latches automatically locking the parts when the wheel is drawn back by the operator after taking his seat.

To facilitate the operating of the latches, a sleeve E, as shown in Fig. 4, may be provided which is slipped on the hub of the head C, free to turn thereon, and connecting the pins D' of the latches with said sleeve by connecting-rods E', so that when the sleeve is turned by the operator the latches will be drawn toward each other and disengaged from the notches of the wheel.

Fig. 5 shows other means for locking the wheel in place on the head C, consisting of a vertical locking-pin F, which extends up- 100

ward through an opening in the extended portion C³ of the head to engage any one of a series of openings F' in the bottom of the rib B'. This pin F is operated by a bell-crank lever F², pivoted at F³ to the head and provided with a slot at one end engaged by a pin on the end of the arm F². A spring F⁴ is provided to normally hold the bell-crank in a position to force the pin F into the openings F', and by providing a series of these openings the wheel may be locked in any position to which it may be adjusted, so that it may be in a convenient position for that particular operator or may be pushed forward out of the way in getting in or out.

The rim or hand-grip B⁴ of the wheel B is preferably round and secured to the outer ends of the arms of the spider B² by screws and also by small tug-pins or lugs B⁵ on the arms, which project into the rim and take the tugging or strain which would otherwise come on the screws and tend to cause them to work loose. Fig. 6 shows the steering-shaft A bent at right angles at its upper end to form the head, and the upper side of this bent end is provided with an undercut groove C' to receive a correspondingly-formed tongue or rib on the wheel.

Having thus fully described my invention, what I claim is—

1. The combination with a shaft and a hand-wheel, of a head on the shaft, and means whereby the wheel is attached to the head to turn the shaft free to slide in a plane at right angles thereto.

2. The combination with a vertically-extending shaft, of a head on said shaft, and a hand-wheel secured to said head to turn the shaft and shiftable thereon in a plane at substantially right angles thereto.

3. The combination with a shaft, of a head on said shaft, a hand-wheel having a sliding engagement with said head free to move in a plane at substantially right angles to the shaft, and means for locking the wheel to the head.

4. The combination, of a shaft extending substantially a vertical direction, a head

on said shaft, a hand-wheel on said head with its rim extending in substantially a horizontal direction, and means for attaching the wheel to the head to move thereon transversely of the shaft and for maintaining said wheel in its substantially horizontal position throughout said movement.

5. The combination with a shaft, of a head on said shaft, a hand-wheel; means on the head and wheel for uniting the same and guiding the wheel free to slide in a plane at substantially right angles thereto, and means for locking the wheel to the head to turn the shaft.

6. The combination, with a shaft, of a head on the shaft, a hand-wheel, a tongue-and-groove connection between said head and wheel, and means for locking the wheel to the head.

7. The combination, with a shaft, of a head on said shaft having a lateral extension and provided with an undercut groove in the face of the head and extension, a hand-wheel having a corresponding rib on its under side to engage the groove and movable therein, and means for detachably securing the rib within the groove.

8. The combination, with a vertically-extending shaft, of a head secured to the upper end of said shaft having an undercut groove in its upper face and lateral extensions formed with openings, a hand-wheel, a corresponding rib on said wheel to engage said groove, lugs on said wheel having notches, and latches in the openings of said extensions to engage the notches in said lugs.

9. The combination with the steering-shaft, of a head on said shaft, a hand-wheel, means for locking the wheel to the head, and means for shifting the wheel laterally and maintaining the same in its own plane.

In testimony whereof I affix my signature in presence of two witnesses.

PATRICK L. HUSSEY.
